(57) **CLAIM**

The ornamental design for a body of monitor camera, as
shown and described.

DESCRIPTION

FIG. 1 is a top, front and right side perspective view of a
body of monitor camera showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top, front and right side perspective view thereof,
with a lens extended. The extended lens portion is shown for
illustrative purposes only and forms no part of the claimed
design.
